UNITED STATES PATENT OFFICE.

CHARLES PFEIFFER, OF AKRON, OHIO.

CHAIR.

965,932.

Specification of Letters Patent.

Patented Aug. 2, 1910.

Application filed March 26, 1910. Serial No. 551,767.

To all whom it may concern:

Be it known that I, CHARLES PFEIFFER, a citizen of the United States, residing at Akron, in the county of Summit and State 5 of Ohio, have invented new and useful Improvements in Chairs, of which the following is a specification.

This invention relates to improvements in chairs, and the object thereof is to provide 10 a chair having a supporting frame on which the chair seat is pivoted so as to permit horizontal movement of the same, said pivoting means provided with locking means whereby the seat may be locked in a preferred 15 position.

The invention further contemplates providing a chair with a hinged back having 20 adjustable braces to permit the same to be secured in an upright position, lowered to a horizontal position, or adjusted in any 25 intermediate position and there locked.

A further object of the invention is to provide one or both of the side arms of the 30 chair with hinges so that they can be swung 25 downwardly, the chair being provided with locking devices for locking the supports for the arm in an upright position, when desired, said locking device provided with a trigger for releasing it and a spring for 35 normally maintaining the locking device in an operative position for locking the arm in an 40 upright position.

The invention especially contemplates 45 that by providing two similar frames, each 35 equipped with a chair seat and uniting said frames together, the two chairs may be combined into a duplicate chair with each chair seat thereof independently movable, the two 50 capable of being shifted into various positions with respect to each other to form different combinations such as a *tete-à-tete*, a *vis-à-vis*, or when placed in another position the two chairs may constitute a lounge or bed, to the end that a pair of chairs temporarily secured together may serve the purpose of a number of pieces of furniture and make the use of the same comfortable and desirable, thereby providing a useful, ornamental and serviceable article, either for a 55 parlor, library or porch, depending somewhat on the finish imparted to the chair body.

With the foregoing and other objects in view, the invention consists in the novel 60 construction, combination and arrangement of parts constituting the invention to be

hereinafter specifically described and illustrated in the accompanying drawings which form a part hereof wherein is shown the preferred embodiment of the invention, but 60 it is to be understood that changes, variations and modifications can be resorted to which come within the scope of the claims 65 hereunto appended.

In the drawings in which similar reference numerals indicate like parts in the different figures: Figure 1 is a perspective view of two supporting chair frames. Fig. 2 is a perspective view of a single chair, complete. Fig. 3 is a longitudinal sectional 70 view of a portion of the chair seat and the top of the supporting frame and the locking device for securing the seat to the frame. Fig. 4 is a longitudinal sectional view of a portion of the rear of a chair seat, showing 75 the means for hinging the back thereof to the seat. Fig. 5 is a view in section of the chair seat and a portion of one of the arms, illustrating the means for hinging the arm 80 to the seat and locking the same in an upright position; and, Fig. 6 is an inverted plan view of a common locking device for the two uprights of one of the arms.

Referring to the drawings in detail, the 85 reference numerals 1 and 2 denote two 90 chair-supporting frames, each of which is provided with a top 3 in which is a transversely-extending slot 4. The tops 4 are supported by a plurality of legs 5 preferably connected by cross-bars 6. It is contemplated in use that these two supporting frames will be connected by fastening devices, designated in the drawings by the reference numeral 7, so that they may be separated 95 from each other, or united and secured together through the medium of these devices. Mounted on each of the tops 3 is a chair seat 8 having a recess 9 in its under face to receive the headed end 10 of a depending exteriorly-threaded bolt 11 which is adapted to pass through the slot 4 and project below the same to receive a nut 12, above which may be placed a washer 13, if desired. By this construction, when the hand nuts 12 100 are loosened, the chair seats may be shifted toward or away from each other to permit their horizontal revolution without interfering with each other and when arranged in a suitable position the hand nuts may be tightened, thereby fixedly securing each of 105 the chair seats in position.

Each of the chair seats is provided with

one or more arms 14 supported by uprights 15 preferably united by cross-bars 16. The lower ends of the uprights 15 are arranged when the arm is in an upright position to rest upon the upper face of the chair seat 8, and in order to permit it to be swung outwardly and downwardly there is formed in the lower end of each of the uprights 15 a longitudinally-extending slot 17 in which is secured by pins 18 the upper end of a hinge member 19 which comprises a plate of metal provided with a depending portion 20 suitably apertured to receive a pivoting bolt 21 and further provided with a depending catch 22, for a purpose to be later described. The under face of the chair seat 8 is provided with a recess 23 in which and secured by holdfast devices 24 are two plates 25 and 26 each provided with a pair of integral tube-like projections 27, the members of each pair spaced from each other to constitute the other portion of the hinge for the uprights of the arm. The lower apertured end of the hinge member 19 is inserted in the space between the members of each pair 27 of tube-like projections and the pins 21 inserted through the coöperating members of the hinge. Each of the plates 25 and 26 is provided with a downwardly-turned slotted flange 28, the slot in which serves to constitute guiding means for a horizontally-swinging bar 29 pivoted on a pivot 30 placed intermediate the plates 25 and 26 and mounted in said recess 23. The plates 25 and 26 are provided approximately centrally with slotted openings 31 through which the catches 22 on the coöperating hinge members on the uprights 15 of the arms are adapted to pass and project sufficiently to permit the locking bar 29 to engage the notches in each catch and thereby detachably secure the arm in an upright position. The catches 22 on the hinge members 19 of the uprights 15 of each arm will be so formed that the notches therein will be turned in opposite directions with respect to each other, so that when the locking bar 29 is shifted in one direction it will be drawn into operative relation with both catches simultaneously.

Mounted on the plate 26 is a spring 32 to normally hold the locking bar 29 in an operative position to cover a portion of each of the slotted openings 31, but leaving sufficient space for the pointed end of the catches to pass through these openings and permit the inclined faces of the catches to shift the bar sufficiently to allow these catches to pass through the slotted openings a sufficient distance to bring the notched portions thereof into position to coöperate with the locking bar 29 and be thereby temporarily secured from withdrawal and thus hold the uprights of the arm fixedly in position. Secured to one end of the locking bar 29 is a release

trigger 33 preferably secured to the plate 26 by a supporting member 34 in order to permit the outer free end of the trigger 33 to project laterally from the chair seat into a position to be easily manipulated by the user of the chair.

The rear edge of the chair seat 8 is provided with a pair of recesses 35 each separated from the central medial line of the chair and provided with an inwardly-extending narrow slot 36 extending approximately half way the thickness of the chair seat 8 so as to leave the upper surface thereof intact. Secured in each of the slots 36 by means of a pin 37 is an outwardly-projecting bar 38 having near its outer end an aperture to receive a pivot bolt 39 and near its medial portion an aperture to receive a pivot pin 40 positioned within the recess 35.

The back of the chair comprises (preferably) two uprights 41 united near their upper ends by a cross bar 42 and near the lower ends by a cross bar 43 between which preferably extend a plurality of slats 44. The lower ends of each of the uprights 41 is provided with an upwardly-extending medially-placed slot 45 in which is secured by means of pins 46 the upper end of a hinge member 47, the lower end 48 of which is bifurcated to inclose the bar 38 and apertured to receive the pivot bolt 40 so as to permit the back to be swung on the bolts 40 either in a position to rest upon the bar 38 or to be elevated to a substantially upright position. The rear face of each of the uprights 41 slightly above its medial portion is provided with a recess 49 through which extends a pin 50 constituting a pivot for the upper end of a brace rod 51 having an offset apertured head arranged to be freely seated in said recess and be pivoted on the pin 50. The brace rod 51 is wedge-shaped and provided near its end with an aperture for a purpose to be later described; and it is also provided on its inner face with a groove 52 for a purpose to be later described. Coöperating with the brace rod 51 is a second brace rod 53 the upper end of which is wedge-shaped and provided with a longitudinally-extending slot 54 arranged in alignment with the aperture in the lower end of the upper brace rod 51. The upper end of the lower brace rod 53 is provided with an outwardly-extending stud 59 which is adapted to be received in the groove 52 and constitute a guiding member for the upper end of the lower brace rod 53. The lower brace rod 53 will be so positioned that the outer face of the upper end thereof will be in lapping engagement with the inner face of the lower end of the upper brace rod 51. Extending through the apertures in the lower ends of the upper pair of brace rods 51 and also through the longitudinal slots 54 of the lower pair of brace rods is a cross rod 55 having one end thereof threaded and pro-

vided with a thumb nut 56 bearing against the outer face of the lower end of one of the upper rods 51 and with the opposite end of the cross rod provided with a head (not shown) bearing against the outer face of the companion upper brace rod 51. Surrounding the cross rod 55 and extending between the inner faces of the pair of lower brace rods 53 is a tube 57. It will be apparent from this construction that when the thumb nut 56 is tightened it will simultaneously clamp both coöperating bars of the upper and lower brace rods in contacting relation to prevent movement of the upper rods with respect to the lower rods and thereby hold the back of the chair fixedly in a determined position.

In order to render the manipulation of the back of the chair easier and to raise the same automatically when the thumb nut 56 is released, a spring 58 is provided, the lower end of which is secured in a suitable aperture near the under face of the rear portion of the seat 8 and the upper end of said spring 25 is arranged to rest against the rear face of the central slat 44.

In setting up a chair such as has been just described, the two supporting frames 1 and 2 will preferably be brought into a position to cause their inner opposing faces to contact and are then secured together by the fastening devices 7.

If it is desired to revolve either or both of the chair seats the one to be revolved will be released by unscrewing its respective hand nut 12 and is then shifted away from its companion chair sufficiently to permit the revolution of the seat thereof without interfering with the seat on the companion frame, after which the backs or arms of either may be moved in a desired or preferred position and securely locked in position.

From the foregoing it will be seen that this device affords an extremely convenient and desirable piece of furniture, by reason of the fact that it may be changed into such a variety of positions, many of which are not obtainable by any other chair now in use.

I claim:

50 1. The combination with a revolubly-mounted and laterally-shiftable chair seat, of means for fixedly locking said seat in a desired position, one edge of said seat provided with a recess, a laterally-extending 55 bar mounted in said recess and projecting outwardly beyond the edge of said seat, a back for said seat adapted to be mounted thereon, a depending member secured to the lower end of said back and lapping said bar and pivotally-united thereto adjacent to the lateral edge of said seat, a brace bar connected with the rear face of said back and a second brace bar pivotally-connected to the outer terminus of said bar, the inner 60 65 face of said brace bars arranged in lapping

engagement with each other and a clamping device arranged to detachably-hold said brace bars against movement whereby said back is fixedly secured in position.

2. The combination with a revolubly-mounted and laterally-shiftable chair seat, of means for fixedly-locking said seat in a desired position, a plurality of recesses in one of the lateral edges thereof, a projecting bar mounted in each of said recesses and 75 extending laterally therefrom and provided near the outer end thereof with an aperture, a back mounted on said seat, a plurality of downwardly-extending members secured in the lower ends of said back each lapping 80 one of said bars and pivoted thereto, a pair of upper brace rods pivotally-secured to the upper rear face of said back, said brace rods provided with apertures near their lower ends and each further provided with a 85 groove on one of its medial faces, a pair of lower brace rods each pivotally-secured to one of the outer ends of one of said bars, said lower brace rods each provided with a longitudinally-extending slot arranged in 90 alinement with the apertures in the lower ends of said upper pair of brace rods and each further provided with a projecting lug adapted to be received and travel in the groove in one of said upper brace rods, a 95 cross rod extending through the apertures in said upper brace rods and the slots in said lower brace rods, a tubular member surrounding said cross rod and interposed between the inner faces of said lower brace 100 rods and means carried by said cross rod for simultaneously clamping all of said brace rods fixedly and detachably together whereby said back may be moved to a desired position and securely locked by said 105 means.

3. A chair comprising a supporting frame, a chair seat pivotally-mounted on said frame, said chair seat provided near one lateral edge thereof with an opening communicating with a recess formed in the under face of said seat, an arm provided with an upright member one end of which is adapted to be seated on the upper face of said chair seat, a hinge member held to said upright, a second hinge member mounted in said recess coöperating with said first hinge member, a temporary locking member for detachably-holding said upright in position on 110 the upper face of said chair seat, a trigger for releasing said locking member to permit the lateral swinging of said arm and a back for said chair seat hinged thereto and provided with means for securely holding the same at a determined inclination with respect to said seat.

4. A chair comprising a supporting frame, a chair seat mounted on said frame provided near one of the lateral edges thereof with a pair of spaced openings each of which 115 120 125 130

- communicates with a recess formed in the under face of said seat, a pair of hinge members mounted in said recess, an arm embodying two upright members arranged to be positioned on the upper face of said seat, each of said arms provided with a hinge member arranged to coöperate with one of the hinge members in said recess, a catch mounted on each of said arms arranged to project into each of said openings, a spring-pressed common lock mounted in said recess adapted to simultaneously engage each of said catches for locking said arm in an upright position, substantially as described. 6 25
- 15 5. A chair comprising a supporting frame, a chair seat mounted on said frame provided near one of the lateral edges thereof with a pair of spaced openings each of which communicates with a recess formed in the under face of said seat, a pair of hinge mem- 10 20
- bers mounted in said recess, an arm embodying two upright members arranged to be positioned on the upper face of said seat, each of said arms provided with a hinge member arranged to coöperate with one of the hinge members in said recess, a catch mounted on each of said arms arranged to project into each of said openings, a spring-pressed common lock mounted in said recess adapted to engage simultaneously each of said catches 30 for locking said arm in an upright position and a trigger carried by said lock for actuating the same, substantially as described. 35
- In testimony whereof I have hereunto set my hand in presence of two subscribing witnesses.
